LADDER

Noël L. Dahlander, New Milford, Pa.

Application August 22, 1944, Serial No. 550,544

4 Claims. (Cl. 228—40)

This invention relates to ladders in general, both single and multiple, so extensively used today on vessels for emergency debarkation purposes.

Among the objects of the present invention it is aimed to provide an improved ladder suitable not only as a single or pilot's ladder, but also as a multiple or debarkation ladder having rigid metal rungs, flexible suspensory elements such as chains and pivotal connections between the chains and the suspensory elements.

It is still another object of the present invention to provide an improved rung for a marine ladder, whether single or multiple, which may conveniently be pivotally connected to the suspensory elements and composed of sheet metal folded back upon itself for reenforcement purposes and reversible to serve as a step whether the ladder is suspended in normal position with its upper ends at the top or in reverse position with its lower ends at the top, the reversible feature being particularly valuable when an emergency debarkation is required at night, at which time, in the interest of protection, as little illumination as possible is used, with the consequent difficulty of securing a ladder of this type in place if its usefulness was not satisfactory unless suspended in one and only one way.

It is still another object of the present invention to provide an improved rung for a marine ladder, whether single or multiple, and converting the T-shaped construction disclosed in the co-pending application for patent, Ser. No. 547,830, filed August 3, 1944, into a reversible rung whereby the ladder equipped with such rungs may be used whether the ends of the suspensory elements normally at the top are at the top or at the bottom.

These and other features, capabilities and advantages of the invention will appear from the subjoined detail description of specific embodiments thereof illustrated in the accompanying drawing in which

Figure 1 is a front elevation of a ladder equipped according to one embodiment of this invention.

Fig. 2 is a fragmental enlarged front elevational detail of the embodiment shown in Figure 1.

Fig. 3 is a section on the line 3—3 of Fig. 2.

Fig. 4 is a plan view of the embodiment of the rung illustrated in Fig. 2 partly broken away.

Fig. 5 is a plan view of a rung made according to another embodiment.

Fig. 6 is a section on the line 6—6 of Fig. 5.

Fig. 7 is a fragmental diagrammatic view of a

multiple ladder made according to the present invention.

In the embodiment shown in Figs. 1 to 4, inclusive, there is illustrated a single ladder composed essentially of two suspensory members 1 and 2 and rungs 3 pivotally connected to said suspensory members 1 and 2. The suspensory members 1 and 2 preferably are flexible and in the present instance are shown as composed of chains of the "Lock Link" type connected to the lash receiving rings 4 at their upper ends, and the chains are preferably covered with socks or envelopes 5 composed of a suitable fabric material such as canvas, see the co-pending application for patent, case #12, of Frederick A. Ellis, Serial No. 547,830, filed August 3, 1944.

The rungs 3 in this embodiment are shown as composed of two pieces of sheet metal 6 and 7, the piece 6 having a lower flange 8 folded under the tread portion 9 which continues into another flange 10 and then terminates in a shank portion 11. The ends, or rather edges, of the tread portion 9 with their reenforcing flanges 8 and 10, are slightly inclined toward the shank portion 11 as shown at 12 and 13. To this piece 6, the piece 7, substantially identically constructed, is secured, it being secured to the piece 6 by welding or the like. The piece 7 consists of the flanges 14 and 15, tread portion 16 and shank portion 17, the shank portion 17 being secured adjacent to the shank portion 11 so that these pieces 6 and 7 complement one another to form an H or I formation in cross section.

In this embodiment the loops 18 and 19 formed at the ends of the rungs 3 are integral with and continuations of the shank portions 11 and 17, respectively, the loop 18 being an integral part of the strip 20 which is folded over and secured by a rivet 21 or the like to the shank portions 17 and 11, the loop 19 in turn being an integral part of the strip 22 which is folded over and secured by a rivet 23 or the like to the shank portions 11 and 17.

Excellent results have been achieved when the rung just described is composed of steel ranging from .031 to .037 inch in thickness, with the steel being galvanized.

In the embodiment shown in Figs. 5 and 6, the loops 24 and 25 are parts of separate clips, the loop 24 having the side arms 26 and 27 and the loop 25 having the side arms 28 and 29 secured to the shank portions 30 and 31 by rivets 32. Preferably, as shown in Fig. 5, two rivets 32, 32 are provided for each loop forming clip 24, 25, the shanks 30 and 31 being portions of the pieces

33 and 34 similar to the portions 6 and 7, respectively, of the embodiment illustrated in Fig. 3, except as already set forth that the loops 24, 25 are parts of separate clips in the embodiment shown in Fig. 6 and in the embodiment shown in Fig. 3 the loops 18 and 19 are integral parts of the pieces 6 and 7, respectively.

When the loop forming clips 24, 25 are separate from the pieces 33 and 34, the pieces 33 and 34 need not be welded to one another, but may depend upon the rivets 32 for securing them to one another. Excellent results have been achieved when the pieces 33 and 34 are composed of sheet steel having a thickness ranging from .031 to .037 inch and the clips forming the loops 24 and 25 have been composed of sheet steel having a thickness ranging from .078 to .125 inch, and all pieces suitably galvanized.

On the other hand, excellent results have also been achieved when the pieces 33 and 34 were composed of sheet aluminum having a thickness of about .081 inch when the clips forming the loops 24 and 25 would be made of steel approximating .125 inch, with the clips galvanized.

Excellent results have also been achieved when the H or I construction formed by the sections 33 and 34 were made in one piece of aluminum, either special rolled or in a casting, having a mean thickness of .156 to .162 inch.

In the embodiment shown in Fig. 7, there is illustrated a multiple ladder in which the rungs 35 secured to the suspensory members 36, 37 and 38 have the same H or I formation in cross section as the embodiments illustrated in Figs. 3 and 6. With the multiple ladder the clips forming the loops 18, 19 or 24, 25 may either be integral with the rung proper as shown in Fig. 4, or separate as shown in Fig. 5. With a rung having an I shape in cross section, a tread will of course be in position for use, that is, face upwardly whether the normal upper ends of the ladder are secured at the top or whether the normal lower ends of the ladder are secured at the top, thus forming a reversible ladder not only having all of the advantages of a rung T shape in cross section, but additional advantages flowing from the added strength that is made possible with an I shaped construction as compared to a T shaped construction.

It is obvious that various changes and modifications may be made to the details of construction without departing from the general spirit of the invention as set forth in the appended claims.

I claim:

1. The combination of a plurality of suspensory members composed of chain links, rungs, each rung composed of two sheets of metal, each sheet consisting of an upper tread portion, a short extension, and a long extension, the short extension being folded back into intimate engagement with the lower face of about one half of said tread portion, the long extension being composed of two webs bent into a dihedral right angle, with one web folded back into intimate engagement with the other half of the lower face of said tread portion, and the other web extending at right angles to said tread portion to form a single thickness shank, the shanks being welded to one another to form a double thickness intermediate web between the tread portions, and clips at the ends of the intermediate web portion having loops forming journals for

link portions of the suspensory members, said clips also having arms riveted to the ends of said shanks.

2. The combination of a plurality of suspensory members composed of chain links, rungs, each rung composed of two pieces of galvanized sheet steel, each sheet being folded back upon itself to form a double tread portion and a single thickness shank portion extending at right angles to the middle of the double tread portion, the shank portions serving as anchoring means for said two pieces and being secured to one another to form a double thickness intermediate web between tread portions, and galvanized steel clips at the ends of each web portion having loops to form journals for parts of the chain links and maintaining the tread portions at the top and bottom in the interest of reversibility.

3. The combination of a plurality of suspensory members, reversible rungs I shaped in cross section with the cross pieces formed at the top and bottom of the intermediate web, each rung composed of two sheets of metal, each sheet consisting of an upper tread portion, a short extension, and a long extension, the short extension being folded back into intimate engagement with about half of the lower face of said upper tread portion, the long extension having two webs forming a dihedral right angle with one web folded under and in intimate engagement with the lower face of the other half of said upper tread portion and the other web extending at right angles to said upper tread portion to form a single thickness shank, the shanks forming anchoring means for the two sheets of metal, and being secured to one another in intimate engagement with one another to form an intermediate double thickness web between the tread portions, and clips at the ends of the intermediate double thickness web portion having loops forming journals for link portions of the suspensory members, said clips also having arms riveted to the ends of said double thickness intermediate web.

4. The combination of a plurality of flexible suspensory members, reversible rungs, each rung composed of two sheets of metal, each sheet consisting of an upper tread portion, a short extension, and a long extension, the short extension having two webs forming a dihedral right angle including a long web and a short web, the long web being folded back into intimate engagement with about half of the lower face of the upper tread portion and the short web extending at right angles to said tread portion, the long extension having two webs forming a dihedral right angle with one another, one web being folded back into intimate engagement with the other half of the lower face of the said tread portion and the other web extending at right angles to said tread portion in intimate engagement with the other web of said short extension, and then extending beyond the said short extension to form a single thickness shank, the shanks forming anchoring means for the two sheets of metal and being secured to one another to form an intermediate double web portion between the tread portions, and clips at the ends of the intermediate web portion having loops forming journals for link portions of the suspensory members, said clips also having arms riveted to the ends of said intermediate double thickness web.

NÖEL L. DAHLANDER.
